UNITED STATES PATENT OFFICE.

DAVID S. WILLIAMS, OF PHILADELPHIA, PENNSYLVANIA.

DESIGN FOR A LAMP-BODY.

SPECIFICATION forming part of Design No. 31,969, dated December 12, 1899.

Application filed November 11, 1899. Serial No. 736,705. Term of patent 7 years.

To all whom it may concern:

Be it known that I, DAVID S. WILLIAMS, a citizen of the United States of America, residing at No. 903 Walnut street, in the city and county of Philadelphia, State of Pennsylvania, have invented certain new and useful Improvements in a Design for a Lamp-Body, of which the following is a specification.

My invention relates to a new and original design for the lamp-body or commingling-chamber of a petroleum incandescent lamp, and is more particularly adapted to that class of lamps producing a light of high candle-power with an incandescent mantle by the use of kerosene-oil vapor under considerable pressure.

Referring to the accompanying drawings, forming part of this specification, Figure 1 illustrates a perspective view of a lamp-body or commingling-chamber, showing my new design. Fig. 2 represents a side elevation, and Fig. 3 shows a front elevation, of the same.

As illustrated in the drawings, the leading or material feature of my design consists of a straight vertically-disposed tube or chamber A, which is provided at the top with a conical portion B and at the lower end with diverging curved branches C and C', provided at their respective ends with cylindrical burner-heads D and D'. 25
30

Having described my invention, what I claim as new, and desire to secure by Letters Patent, is—

The design for a lamp-body as herein shown and described. 35

Signed by me at Philadelphia, Pennsylvania, this 10th day of November, 1899.

DAVID S. WILLIAMS.
